Ind., a corporation of Indiana

Application November 25, 1947, Serial No. 787,997

20 Claims. (Cl. 155—178)

1

The present invention relates to theater chairs and more particularly to the back constructions thereof.

Chairs of the general type to which the invention relates are extensively used in motion picture theaters and similar auditoriums and the like where they are arranged side by side in substantially parallel straight or curved rows. Each chair comprises a seat member mounted in or on a supporting member which is fixed in position relative to the floor and to adjacent supporting members arranged in the row. The seat member may or may not be mounted pivotally or be otherwise hinged to the supporting member for folding movement between a horizontal operative position and a vertical inoperative position, but in any case the supporting member includes a pair of side standards and a back member or element which is secured to and between the side standards at about the rear edges thereof.

Most modern chairs are upholstered, i. e., the seat and back elements are provided with cushion fillings covered by leather or an upholstery fabric. These surfaces are subject to wearing at a considerably greater rate than the rest of the chair construction, which is made of more durable materials, such as metal and wood. Because chairs located in certain more desirable parts of any auditorium are more frequently occupied than the chairs located elsewhere, in less desirable parts of the auditorium, the former chairs are subjected to a more rapid rate of wear than the latter chairs and more frequently need replacement or removal for repair.

It is desirable to change from time to time the worn parts of the more frequently used chairs and exchange them for the less worn parts of other chairs in the auditorium, thus more or less equalizing the wear on all the chairs of the installation.

Because the seat members are commonly and easily made readily removable from the fixed supporting member, it is a simple matter to switch or exchange the seat members. However, in the best prior art constructions of which I am aware the upholstered back elements of the fixed supporting structures are more or less permanently attached to the side standards, which in turn are more or less permanently secured to the floor. Consequently, the removal of a back element from one part of an auditorium to another has heretofore required removal of the entire supporting structure, including the durable and generally unworn side standards thereof, and has involved the difficult and time-consuming operations of detaching the legs of the side standards from

2

the floor, carrying the whole side standard with its attached back element from one location to another, and reattaching it to the floor in the new location. In some of the prior art constructions portions of the side standards have been made detachable from the fixed legs of the standards, but even in such cases removal of the back members has required that the attached side standard structure be removed with them.

10 The principal object of the present invention is to eliminate the inconvenience and expense of these operations by removing the need for them which, according to the principles of the invention, is accomplished by mounting the back element for ready removability from the side standards of the supporting structure. Thus the whole structure of the side standards, with or without the seat member, may be left in permanently fixed position and the back element may be 20 quickly detached, removed and replaced by another back member, taken from new stock or from some other pair of side standards in a less used location in the same general installation.

A further object is to provide a construction 25 of this type in which the back element can be removed and attached by unskilled labor using nothing more than common and simple tools.

Another object is to provide an arrangement 30 of the type described in which the mode of removing a back element is not obvious to an uninformed person, and in which the actuating device for effecting the removal is concealed, and in which the movement of the parts required for effecting separation of the back element from its mounting is normally blocked when the parts 35 are all assembled in operative relation, so that no inquisitive or mischievous occupant of a seat will normally be able to dismantle the construction.

A more specific object is to mount a chair back 40 for removal by a forwardly swinging movement which, since the mounted back slopes up to the rear, permits the back to be manipulated for both attachment and detachment by movement through a path which is entirely in front of the 45 vertical plane of its part which projects farthest to the rear when the parts are all assembled, thus permitting the attachment and detachment of the backs of chairs which are set close up against a wall, such as the chairs of the rearmost row 50 of an auditorium.

Further objects are to provide an arrangement 55 of the class described in simple, inexpensive, durable and foolproof form.

Other objects and advantages will be apparent to those skilled in the art from the present dis-

closure of a preferred embodiment of the invention which has been thoroughly tested in actual practice and found entirely satisfactory.

Generally speaking, the above stated objects and other incidental advantages are accomplished and obtained by mounting the back member on the side standard members by a latching arrangement which is operable to latched and unlatched positions by actuating a control element positioned on one of the members in normally concealed position. I find it preferable to use interfitting detents as the latching means, embodied in the form of a tongued plate movable in relation to each side member to enter and be withdrawn from sockets in the back member. I find it also convenient to use arm rests which surmount the side standards and are made difficultly removable therefrom to act as stops for blocking and preventing movement of the latching means to back-releasing position. It will be appreciated that within the broad principles of the invention the arrangement of the latching parts may be reversed, the actuating member may be located on the back member or on the side standards, and movement to unlatching position may be blocked by part other than the arm rest, or the blocking feature may even be omitted.

With the foregoing broad principles of the invention in mind, the particular embodiment which is shown in the accompanying drawings, and which is preferred as constituting the best manner in which I contemplate practicing the invention, will now be described.

In the drawings,

Figure 1 is a perspective view of a complete chair embodying the principles of the invention;

Fig. 2 is a side elevational view of such a chair;

Fig. 3 is a vertical cross-sectional view taken through one of the side standards and adjacent portions of the seat member along the line 3—3 of Fig. 2;

Fig. 4 is a vertical cross-sectional view taken through one of the side standards along the line 4—4 of Fig. 2;

Fig. 5 is a vertical sectional view taken through the back element and showing, principally in side elevation, one of the side standards;

Fig. 6 is a top plan view of one of the side standards with the arm rest removed;

Fig. 7 is a horizontal sectional view through a side standard, taken along the line 7—7 of Fig. 5;

Fig. 8 is a similar view taken on the line 8—8 of Fig. 5;

Fig. 9 is a detail horizontal sectional view, on a relatively enlarged scale, taken on the line 9—9 of Fig. 5; and

Fig. 10 is a front elevational view of one of the side portions of the back element, showing in cross section the interfitting lug devices of the adjacent side standard.

The illustrated embodiment of the invention includes a supporting member 1 having a back portion 2 rigidly held by and between side standards 3 provided with feet 4 which may or may not be connected by cross braces 5 and which are intended to be securely affixed to the floor. The supporting member mounts a seat assembly 6 comprising an upholstered top 7 secured to a bottom pan 8 which is best made of sheet metal and which encloses the usual upholstery springs, webbing, filling, etc.

Although shown in the drawing as a single, independent unit, in actual practice the chairs

are preferably arranged in multiple in a row, with each of the side standards 3, except those at the extreme ends of the row, providing mounting for a pair of seat assemblies, one on each side of each side standard.

The seat 6 in the illustrated embodiment is pivotally mounted for movement between a horizontal operative position and a vertical inoperative position by means which forms the subject matter of my separate copending application Serial No. 787,996, filed November 25, 1947, and which is best illustrated in Fig. 3. It is believed to be sufficient here to explain simply that this pivotal mounting arrangement, which forms no part of the claimed subject matter of the present application, comprises providing on each side standard 3, beneath the arm rest 9 which surmounts the inner frame 10, an inner trimming plate 11, with an upstanding tongue 13, formed in a bulge 12 in the plate 11, to act as a post for receiving the socket 14 which is carried by the seat pan 8. This socket member has a stout post 15 fixed securely to it and projecting horizontally through an elongated slot 15a a short distance into the interior of the seat pan, where it carries a distorted gear 16 which is meshed with an internal rack 17 fixed to the seat pan to ride on the gear as the seat member is pivoted, so as to cause the seat member to be elevated bodily as it is swung to upraised position and to be lowered bodily as it is swung to horizontal position. A plate 19 may be secured across the inner faces of the rack and gear and an uplift spring 20 may be mounted between the post 15 and a pin 21 instanding from the plate 19. The whole pivoting structure may be inwardly enclosed by a plate 22 having its upper edge downturned at 23 over the margins of the pan wall 8 and the trimming plate 19.

The present invention is concerned more particularly with the connection of the back element 2 to the side standards 3 by an arrangement which will now be described in detail in terms of its embodiment in the illustrated construction.

As has been explained, each supporting structure 1 comprises a pair of side standards 3 and an interposed back element 2. Each side standard includes a stout inner frame member 10 in the form of a substantial casting or the like, conveniently made of iron, in the form of two slightly curved upright members of generally T-shaped cross section. These are connected slightly below their midportion by an upwardly opening channel 24 which is welded to the two members, and they are further connected by an upper channel member 25 which has its top opening at the level of the upper edges of the members. The two channels and their relation to the rest of the side standard structure are best shown in Figs. 3 and 4, from which it will be appreciated that they make up a very rigid side standard frame.

The inner trimming plate 11 is provided along its top edge with a groove-like depression surmounted by an outwardly turned horizontal portion 26 having a downwardly directed flange 27 and at its lower edge with an inwardly turned horizontal portion having a downwardly turned flange 28, and these two flanges are fitted respectively into the upper and lower channels 25 and 24. The front and rear margins of the plate are flanged and fitted behind the uprights of the frame member 10, as shown in Figs. 6-8, so that the plate is slidable vertically into and out of position on the frame.

In the illustrated embodiment of the invention the chair is shown with a trimming plate 11 mounted on the inner side only of each of the two side standards. An outer trimming plate 29 is attached to the outer side of each of the standards. This plate has vertical flanges 30 inturned along its front and rear edges and seated behind the uprights of the frame member 10, as shown in Figs. 6-8, and has along its top edge a reversely bent horizontal bead formation 31 terminating in a downwardly directed flange 32 which is set in the channel 25, as shown in Figs. 3 and 4. Thus the outer plate 29 is held in the side standard assembly and is made slidable into and out of position thereon, like the plate 11.

It will be appreciated that each frame member 10 and its associated channels 24 and 25 is capable of supporting on either of its sides a plate 11 or a plate 29. In actual practice with the chairs arranged in multiple in a row, both frame members of each chair except the chairs at the ends of the row mount a pair of plates 11, so that each side standard in the row except the two endmost ones supports two seat assemblies, one on each side. The row is trimmed at its ends only by plates 29 mounted on the outer sides of the endmost side standard frame members 10. These plates 29 are structurally quite plain, since they function simply to enclose and trim the frames, but they may be provided with any suitable ornamentation and with openings like that shown at 33 for emitting rays from an aisle light (not shown) which may be socketed inside the standard.

The horizontal portions 26 of the two plates 11 of a side standard, or the combination of such a portion and the bead formation 31 of a plate 29, form an undercut tongue which is made slightly tapered at its front, or slightly flaring from front to rear, as shown in Fig. 6, to make good tight frictional fit with a complementally shaped socket member 34 which is secured to the forward portion of the underside of the arm rest 9. Thus an arm rest can be slid as indicated in Fig. 5 into position on any side standard, as shown in Figs. 3 and 4.

Besides mounting the seat member supporting tongue or post 13, each inner trimming plate 11 carries the complete assembly which latches the back element 2 onto the side standards for quick attachment and detachment. This assembly will now be described.

The plate 11 is outwardly offset along the line 35, shown in Fig. 5, to provide a relatively shallow depression which extends back to the rear edge of the plate and this depression is filled with an external plate 36 and an internal plate 37, which are spaced part adjacent to the offset 35 by a filler plate 38. These three plates, 36, 37 and 38 may all be spotwelded to each other and to the plate 11, and the space between the plates 36 and 37, to the rear of the filler plate 38, is occupied by a vertically movable latch plate 39.

This latch plate is provided along its rear edge with a series of lugs 40 which stand between somewhat similarly shaped upstanding matching projections or teeth 41 formed on the two plates 36 and 37. The combination of each lug 40 and adjacent projection 41 forms a lug device or a latch element. The lower surfaces of the lugs 40 are notched at their inner ends, and the upper surfaces of the projections 41 are similarly notched, as shown in Fig. 5. The latch plate is made movable up and down by rotation of a cam or eccentric disc 42 which is

positioned for rotation in a generally elliptical opening 43 in the latch plate and which is journaled in bearing holes provided in appropriately shaped bulges formed in the plates 36 and 37, as best shown in Fig. 4.

The cam 42 has axially short cylindrical trunnions projecting from its two side faces which are journaled in the bearing openings formed in the bulges in the plates 36 and 37. One of these trunnions extends through the opening in the plate 36 and is provided with a slot 44 for reception of a screw driver blade or the like by which the cam may be turned to cause its projecting nose to bear against one or the other of the elliptical sides of the opening in the latch 39 to raise or lower the plate, depending on which way the cam is turned. When the plate is raised to the limit of its upper position, which is determined by engagement of its front edge with the rear edge of the filler plate 38, the latch lugs 40 are raised entirely up within the confines of the projections 41 on the plates 36 and 37, so that the over-all area of the projections with the lugs withdrawn between them is simply that of the projections. However, when the latch plate is lowered by oppositely turning the cam, the lugs 40 are projected downwardly from between the projections 41, and the over-all area of the lugs and projections is increased.

The back element 2 is made in any convenient form and style, with a central front area covered by upholstery material 45 and with a surrounding edge 46 of metal in which the margins of the material are mounted. It is convenient to make the entire back surface of the seat member in the form of a sheet metal shell 47, which is turned forwardly at the side edges, as shown in Figs. 1 and 2.

The front side margins 46 of the sheet metal of the back element are provided with a vertical series of openings 43a, each adapted to act as a socket for receiving one of the projection and lug combinations 40 and 41 when the lugs are retracted within the confines of the projections. This is easily accomplished by turning the cam counterclockwise as viewed in Fig. 5 so as to retract the lugs. Then the topmost pair of projections 41 which, as appears in Fig. 5, are upwardly elongated, can be fitted into the topmost pair of sockets 48, with the bottom of the back element 2 tilted slightly to the rear. Thus engaged with and hung on the topmost lugs of both side standards, the back element can be swung forwardly in against the two side standards to fit all the other projections into the corresponding sockets. The back is securely held and automatically guided in this swinging movement by the ample interfit of the specially elongated topmost lugs 41 in the topmost back sockets 48. Rotation of the cam to its clockwise limit then lowers the latch plate 39 to extend the lugs 40 down from between the projections 41 so as to catch the metal 46 of the back member shell 47 in front of each of the lugs. Thus the back element is securely held in position on the side standards.

The latch plate 39 is made to project appreciably, as shown at 49, below the bottom edges of the plates 36 and 37, and to have its top edge 50 aligned at the level of the top edges of the plates 36 and 37, closely beneath the bottom surface of the arm rest 9, behind the socket member 34, when the latch plate is in latching position with the lugs 40 downwardly projected. This arrangement is productive of several ad-

vantages. It prevents elevating the latch plate to unlatching position when the arm rest is mounted in position on the side standards, thus requiring removal of the arm rest preliminary to removal of the back element. It also provides the conveniently projecting portion 49 of the latch plate which needs only to be struck up to elevate the plate to unlatching position. Thus, in case the parts become rusted or corroded after a long period of use and it is difficult to turn the cam 42 by means of a screw driver, the projecting portion 49 can be struck by a hammer and readily knocked loose.

It is convenient to make the extreme outer edges of the projections 41 with slight inward offsets, so that the outer edges normally engage each other, as is best shown in Fig. 9. This encloses each of the lugs 40 and gives the entire assembly a thin edge for more readily penetrating the sockets 48. It is also convenient to strike dimples into the projections 41 to provide small circular protuberances 51 for fitting into small circular holes 52 in the lugs 40 when the lugs are retracted up into the space between the projections. When the lugs are projected down from the space between the projections the holes 52 move from the protuberances 51 and thus the projections become expanded laterally, as shown in broken lines in Fig. 9 to make a tight fit in the sockets 48 formed in the back member.

It is also convenient to provide the two plates 36 and 37 with shoulders 53 along the rear edges, just inwardly of the projections 41. This forms a seat of some width against which the inwardly swinging back member comes abruptly to rest when being mounted.

It is believed that the principal structural and functional features, as well as the mode of operation and the main advantages, of the invention will be well understood from the foregoing explanation. Not all of the features or elements need be included or used in the particular combinations shown, and many of the parts and relationships may be modified from the specific form employed in the illustrated embodiment.

For example, I have stated that the actuating or control element for unlatching the back, which of course is the cam 42, is preferably so located that it is normally concealed and thus made less susceptible to unauthorized tampering. The illustrated embodiment of the invention is a chair of the automatic uplift type, in which the seat member is in vertical position at all times except when occupied. When the seat member is in vertical position it hides the cam, but the cam is readily exposed for access and rotation by simply lowering the seat member. Thus one of the minor objects of the invention is attained without requiring the seat member to be removed preparatory to removing the back. However, if greater protection for the cam is desired, the cam may be positioned lower down on the side standard, so as to be concealed by the seat member when in either of its two terminal positions, thus, however, making it necessary to remove the seat member before the back can be removed or installed.

While the materials of which the several parts are made form no part of the invention, broadly considered, it is convenient and desirable to use metal to make substantially all of the structure, except the arm rests and the upholstery, in accordance with the best modern practice, employing sheet metal stampings wherever possible.

While the primary object of the invention is 75

to make the backs in an installation readily removable and replaceable, it will be noted that the invention makes many other parts easily removable, even though they are inherently less susceptible to wear. Thus, with the arm rests removed, the plate 11 and the plate 29, with all its appurtenant parts, can be lifted from the framing members 10. Moreover, the assemblies carried by the plates 11 can be dismantled by 10 prying the plates 36 and 37 apart to permit the latch plate 39 and the cam 42 to drop out from between the plates, although it is hardly likely that either of the parts 39 or 42 will ever require replacement.

The parts which have been specified as preferably welded to each other are ones that are not expected to require replacement at any time. For example, the assembly of the plates 36 and 37 and the interposed filler plate 38 is 15 conveniently made by spotwelding the three plates together, and the assembly may be permanently mounted on the plate 11 by spotwelding the plate 37 to the plate 11. This welding may be direct and immediate, or a filler plate 54 20 may be interposed, as shown in Figs. 6-8, to separate and space the assembly somewhat from the plate 11. This is desirable to give an appropriate camber to the two assemblies of a given chair so that their projections 41 will 25 be accurately spaced horizontally apart by the exact distance between the two lines of sockets 43 of a back member. Any slight inaccuracy in this spacing of the projections can be corrected by bending the free rear edges of the assemblies toward or away from the plate 11, and, even more important, these edges can be bent to compensate for the slightly angular, instead of accurately parallel, setting of the side standards of chairs arranged in a curved row.

I claim:

1. A theater chair comprising a fixed supporting member, a back member, and means 40 separably connecting the members together comprising a socket formed in one of the members, a lug device projecting from the other member insertible into and expansible in the socket, and an actuating element connected to the lug device for expanding it.

2. A theater chair comprising a fixed supporting member, a back member, and means for 45 separably connecting the members together comprising a socket formed in the back member, a lug device projecting from the supporting member insertible into and expansible in the socket, and an actuating element connected to the lug device for expanding it.

3. A theater chair comprising a fixed supporting member, a back member, and means for 50 separably connecting the members together comprising a substantially vertical line of separate sockets formed in the front margin of each side of the back member, a lug device projecting from the supporting member and insertible into and expansible in each of the sockets, and an actuating element connected to the lug device for expanding it.

4. A theater chair comprising a fixed supporting member, a back member, and means for 55 separably connecting the members together comprising a socket formed in the back member, a projection extending in fixed relation from the fixed supporting member, a lug juxtaposed to the projection and movable with relation thereto so that in one position of the lug the lug and projection are insertible together into the socket and in another position of the lug

the lug and projection are expandable and thereby held within the socket, and an actuating element connected to the lug for moving it selectively to said two positions.

5. A theater chair comprising a fixed supporting member, a back member, and means for separably connecting the members together comprising a socket formed in the front face of each side margin of the back member, a lug device projecting from the supporting member and insertible into and expandable in each of the sockets, and an actuating element connected to the lug device for expanding it.

6. A theater chair comprising a fixed supporting member, a back member, and means for separably connecting the members together comprising a vertical line of separate sockets formed in the front margin of each side edge of the back member, a plate having a vertical line of separate projections extending in fixed relation from the supporting member at the rear of each side thereof, a lug juxtaposed to each projection of said plate and movable with relation thereto so that in one position of each lug the lug and adjacent projection are insertible together into the socket and in another position of the lug and adjacent projection are expanded and thereby held within the socket, and an actuating element connected to the lug for moving it selectively to said two positions.

7. A theater chair comprising a fixed supporting member, a back member, and means for separably connecting the members together comprising a plurality of sockets formed in the back member, a corresponding plurality of projections extending from the back of the fixed supporting member, and movable plate means having a corresponding plurality of lugs juxtaposed to the projections and movable with relation thereto so that in one position of the plate means the lugs and projections are insertible together into the sockets and in another position of the plate means the lugs are displaced from the projections and thereby held within the sockets.

8. A theater chair comprising a fixed supporting member, a back member, and means for separably connecting the members together comprising a plurality of sockets formed in the back member, a corresponding plurality of projections extending from the back of the fixed supporting member, movable plate means having a corresponding plurality of lugs juxtaposed to the projections and movable with relation thereto so that in one position of the plate means the lugs and projections are insertible together into the sockets and in another position of the plate means the lugs are displaced from the projections and thereby held within the sockets, and means for moving the plate means between its two positions comprising a cam mounted in the fixed supporting member and rotatable in an opening formed in the plate means.

9. In a theater chair having a side standard, an arm rest detachably mounted thereon, and a back member, means for separably connecting the back member to the side standard comprising a socket formed in the back member, a projection extending from the side standard, a plate movable on the side standard and having a lug juxtaposed to the projection so that in one position of the plate the lug and projection are insertible together into the socket and in another position of the plate the lug is displaced from the projection and thereby held within the socket, and a portion of the plate being engageable with

the arm rest to prevent movement of the lug from expanded position.

10. A theater chair comprising a fixed supporting member having a movable portion and including a side standard, a back member, and means for separably connecting the back member to the side standard comprising a socket formed in the back member, a projection extending from the side standard, a plate mounted on the side standard for movement relatively thereto and having a lug juxtaposed to the projection so that in one position of the plate the lug and projection are insertible together into the socket and in another position of the plate the lug is displaced from the projection and thereby held within the socket, and a portion of the plate being engageable with the movable portion of the fixed supporting member when the plate is in the first named position, so that said portion must be moved before the plate can be moved to the second named position.

11. A theater chair comprising a fixed supporting member, a back member, and means for separably connecting the members together comprising a socket formed in the back member, an expandable and contractile element carried by the supporting member insertible into the socket when in contracted condition and engaged in the socket so as to be non-removable therefrom when in expanded condition, and an actuating element connected to the first named element for expanding and contracting it.

12. A theater chair comprising a fixed supporting member including a pair of side standards, a back member, and means for separably connecting the members together comprising a pair of sockets formed on the front face of the back member at the opposite side margins thereof, a contractile and expandable element carried on each side standard insertible into a socket when in contracted condition and engaged in the socket so as to be non-removable therefrom when in expanded condition, and an actuating element connected to the first named element for expanding and contracting it.

13. A theater chair comprising a fixed supporting member including a pair of side standards and a seat mounted thereon for movement between a horizontal operative position and a vertical inoperative position, a back member, and means for separably connecting the members together comprising a socket formed on the back member, a contractile and expandable element carried by a side standard insertible into the socket when in contracted condition and engaged in the socket so as to be non-removable therefrom when in expanded condition, and means for contracting and expanding the element mounted on a side standard and inaccessible for operation when the seat is in one of its named positions.

14. A theater chair comprising a fixed supporting member, a back member, and means for separably connecting the members together comprising a socket formed in the back member, a projection extending from the back of the fixed supporting member, and a plate movably connected to the fixed supporting member and having a lug juxtaposed to the projection and movable with relation thereto so that in one position of the plate the lug and projection are insertible together into the socket and in another position of the plate the lug is displaced from the projection and thereby held within the socket, a portion of the plate projecting from the fixed sup-

porting member when the lug is expanded from the projection so that said projection may be struck a blow by a hammer or the like to assist in moving the plate and the lug to the first named position.

15. In a theater chair having a side standard and a back, means for separably connecting the back to the side standard comprising a socket formed in the back, an expandable and contractile element carried by the side standard and insertible into the socket, and means carried by the side standard movable in one direction to expand the element both vertically and horizontally to make tight fit in the socket and movable oppositely to contract the element both vertically and horizontally to free it from the socket for removal therefrom.

16. In a theater chair having a side standard and a back, means for separably connecting the back to the side standard comprising a socket formed in the back, a pair of fixed plates extending from the rear of the side standard and having matching spaced parallel projections extending therefrom for insertion into said socket, a plate movably connected to the side standard and having a lug extending between said projections and movable with the plate to extend from the projections and expand the projections laterally, thereby holding the projections in the socket and securing the back to the side standard.

17. In a theater chair having a fixed supporting structure including a pair of side standards having upwardly and rearwardly sloping rear edges, a back having its side margins normally engaged with the rear edges of the side standards so that the back is inclined upwardly and rearwardly, and means normally latching the back to said edges movable to unlatching position for release of the back so that the back is removable by a rearward swinging movement followed by a lifting movement.

18. In a theater chair having a fixed supporting structure including a pair of side standards having upwardly and rearwardly sloping rear edges, a back having its side margins normally engaged with the rear edges of the side standards so that the back is inclined upwardly and rearwardly, means normally latching the back to said edges comprising a plurality of latch elements arranged along the rear edge of each side standard and insertible into holes in the back, and means for unlatching said elements to release the back so that the back is removable by swinging its top edge forward to free all except the topmost elements

from the corresponding holes in the back, followed by lifting of the back to separate it from the topmost elements.

19. A theater chair comprising a fixed supporting member including a pair of side standards, a separable back member, and means for connecting the back member to the side standards comprising an upwardly projecting lug device extending from the upper portion of the rear edge of each side standard, a socket formed in each side edge of the back member for receiving one of said lug devices so that the back member may be pivotally swung about said devices into engagement with the side standards, and other lug devices and sockets provided on the side standards and back member below the first named lug devices and sockets adapted to become engaged with each other when the back member is swung into engagement with the side standards, and means connected to the last named lug devices for selectively expanding and contracting them within the sockets.

20. A theater chair comprising a fixed supporting member including a pair of side standards, a separable back member, and means for connecting the back member to the side standards comprising an upwardly projecting lug device extending from the upper portion of the rear edge of each side standard, a socket formed in each side edge of the back member for receiving one of said lug devices so that the back member may be pivotally swung about said devices into engagement with the side standards, other lug devices and sockets provided on the side standards and back member below the first named devices and sockets adapted to become engaged with each other when the back member is swung into engagement with the side standards, and means connected to said lug devices for expanding at least some of them in said sockets to maintain the back member engaged with the side standards.
